UNITED STATES PATENT OFFICE.

HERMAN P. ANDRESEN, OF CHICAGO, ILLINOIS.

SIGN.

1,316,756.

Specification of Letters Patent. Patented Sept. 23, 1919.

Application filed March 8, 1919. Serial No. 281,441.

To all whom it may concern:

Be it known that I, HERMAN P. ANDRESEN, a citizen of the United States, and a resident of Chicago, Cook county, State of Illinois, have invented certain new and useful Improvements in Signs, of which the following is a specification.

My invention relates generally to signs and methods for the production thereof, but relates more particularly to signs such as are used out of doors, a typical example of which is a street or road sign.

Signs of this character in order that they may be easily read from a moving vehicle, and in the night as well as the day, must have the greatest possible contrast in colors of characters and background. It has been customary to provide signs which are painted or enameled on wood or metal. Paint wears off, bleaches, and becomes marred or obliterated. For these reasons, frequent repainting by experienced sign letters is necessary and high maintenance cost is the consequence.

Enamel, being very brittle, chips and cracks. As signs are very frequently used as targets by persons shooting and throwing stones or other missiles, they quickly become chipped, and once the enamel is removed from the sheet steel, of which the body of the sign is generally composed, the sign rusts, becomes unsightly and illegible. Enamels also bleach until so little contrast remains between characters and background that the sign is no longer readable.

Outdoor signs are, of course, constantly subjected to the elements such as intense sunlight, changes of temperature, rain, snow, etc. Not only does this result in bleaching and loss of contrast in colors of paints and enamels, but also causes warping, splitting and rotting of wood or rusting of the metal whichever may form the body of the sign.

The general object of my invention is to provide a sign that shall be the better adapted to withstand service conditions imposed upon an outdoor sign, than those hitherto devised.

Another object of my invention is to provide a sign of such character that the surface thereof will not be easily chipped, cracked, bleached or worn off and that the body of the sign will not become marked, split, broken, rotted or rusted; and in which the contrast between characters and back-

ground shall be maintained without attention, throughout the natural life of the sign, or in any event over a long period of years.

Again it is an object of my invention to provide a sign composed of two different substances, one thereof forming the characters and the other a background, the materials having that characteristic by virtue of which they will maintain their original colors and characteristics when subjected to air, sunlight, water and other outdoor conditions.

A further object of my invention is to provide a method whereby an outdoor sign can be produced rapidly at low cost.

My invention consists generally in the form, composition and arrangements of the materials, and also in the steps, acts and sequence thereof, whereby the above named objects, together with others that will appear hereinafter, are attained; and my invention will be more readily understood by reference to the accompanying drawings wherein I have depicted generally steps to be followed in the production of sign embodying my invention and also the sign as a completed article.

Therein: Figure 1 is a face view of a plate which is to form part of the sign; Fig. 2 illustrates a further step in the production of the sign wherein letters have been formed by offsetting portions of the plate from the original plane of the plate; Fig. 3 is a face view of the complete sign; Fig. 4 is an enlarged sectional view substantially on the line 4-4 of Fig. 3; Fig. 5 is a sectional view similar to Fig. 4, but illustrating a modified form of my invention; Fig. 6 is a sectional view similar to Fig. 4, but illustrating another form of my invention and Fig. 7 is a sectional view similar to Fig. 5 but illustrating still another form of my invention.

In that embodiment of my invention shown in Figs. 1 to 4 of the drawings, I choose a metal plate 1, to serve as one of the materials of the sign. This plate may be composed of different metals or of different metal alloys, but the characteristic of the plate or sheet should be such that when subjected to atmospheric conditions of rain, sunlight, high winds and the abrading action of sand and other materials directed against it, that it will not bleach, oxidize, (rust), or deteriorate, but on the contrary

will maintain its original characteristics of color, form and stability. One such suitable material is aluminum, since it has a relatively light or bright appearance, which in the air or water acquires only a very thin film of closely adhering oxid, acting as a sort of varnish, which in turn prevents further oxidation and action by atmospheric gases and water. I wish it to be understood, however, that the material aluminum, is cited by way of illustration and not by way of limitation, except when expressly so limited in the claims. Thus while I do not consider them so good at the present time, galvanized iron, zinc or aluminum-bronze, or plates of other materials may be used. After choosing the metal plate and giving it the desired form or size, I next form the desired letters therein by offsetting portions of the metal from the original plane of the plate or sheet, forming the word or character desired. For example, in Fig. 2, the word "Will" stands for "Will street or road", is impressed in the plate. At the same time that the letters or characters are formed I also prefer to form a border or ledge 1', which serves to confine the body filler material hereinafter described.

While the plate here shown is a pressed plate, I wish it to be understood that the plate and letters may be cast or formed in any other desired manner. The sign as thus far produced, while it is readable upon close observation and in broad daylight, becomes unreadable at a distance, when moving rapidly in a vehicle or in the dusk or darkness.

As a next step, therefore, I proceed to surround the letters with a mat or body of material of a contrasting character, such as will cause the letters to stand out in bold relief and to be easily visible at a considerable distance, in a dim light and when passing rapidly by the sign. The material that I prefer to utilize for this purpose is one which, like the material from which the letters are formed, is of such character as to maintain its identity both in color, form and stability when subjected to the very severe service conditions before mentioned; and since the material of the plate in the present instance, is aluminum, having a light metallic luster, I prefer to choose for this purpose a bituminous material such as asphaltum, tar, or compounds thereof, for the reason that such materials in color are permanently black, and are substantially unaffected by weather conditions or rain, sunlight, wind, etc., and are themselves weatherproof materials. Materials of this nature have another characteristic which makes them particularly suitable for this purpose and that is, that when subjected to a workable temperature they become sufficiently plastic so that they can be flowed or easily spread upon the plate as may be necessary to form the

mat or border around the letters. Thus in Figs. 3 and 4 the letters 2 are bordered or surrounded by a body of material, 3, preferably having the characteristics just enumerated. The right angular lines upon the face 70 of the sign in Fig. 3 indicates black or a dark color and not roughness of the material.

In Fig. 4 I have shown an enlarged cross section through the sign wherein it will be seen that in this example the letter, 2, is offset outwardly from the original plane of the plate indicated at 8'; and the contrasting material 3 is then placed around it. With a sign of this character the material 3 can be worn or reduced from W to the line W', see Fig. 4 and yet the sign will be absolutely unaltered in appearance or stability and will to all intents and purposes be as easily readable and self-preserved as when originally erected. When the material 3' wears away to the plane 1', the sign can be easily made as good as new by simply spreading or applying quantity of the material 3 around the letters until a body thereof is built up to the desired height or thickness. It is not anticipated that this will ever be necessary especially when one considers that the body of material 3 is not a mere film such as a coat of paint or varnish, but on the contrary is a thick layer or body of material such that it will withstand service conditions over a long period of years. In order to distinguish the thick layer of material 3 from a film of paint or varnish, or enamel, I shall hereinafter refer to it as, a body of filler material.

In the illustration given the letters being formed of the aluminum facing need no attention of any kind, and neither the face 105 of the letter nor the surrounding body of filler material will be chipped off when hit by stone or other missile. While a stone or other missile may make a small dent in the material 3, where it is struck (if struck hard 110 enough) the material is of such consistency that it will not crack or chip and the legibility of the sign is unaffected.

I stated with respect to the formation of the letters in the sheet of metal, that they 115 were formed by offsetting them with respect to the initial plane of the metal, and in the form shown in Figs. 3 and 4, the letters are shown as being offset outwardly, *i. e.*, embossed, but I wish it to be understood that 120 my invention is in no wise limited to such construction. Because the letters instead of being offset outwardly may be offset inwardly, *i. e.*, sunk. Such a construction is shown in Fig. 5 of the drawing wherein 5 represents the original plane of the metal and 5' the offset or countersunk portion, defining a letter of the word or symbol. When such a construction is resorted to the recess provided by the sinking of the metal is pref- 130

erably filled with the asphaltum, tar or other material of the character heretofore described. In this instance, to avoid confusion I have applied the reference character 5 to the body filler material. When the form of my invention shown in Fig. 5 is used and the plate is made of aluminum, it is obvious that the letters are black and that they are surrounded by the light metallic 10 aluminum face, which causes the contrast that enables them to be very easily read. It will also be understood that the body of material 6, being of a very considerable thickness, will withstand service conditions 15 over a long period of years, and in the event that it should wear away eventually, can be very easily replaced. I might here add that in the matter of replacement both in that 20 form of my invention described with reference to Figs. 3 and 4 and with that form of my invention now under discussion, to maintain the well defined and easily readable character of the letters can be accomplished by an ordinary unskilled workman, as in the 25 first instance it is a mere matter of filling the material around the embossed letters and in the other instance the replacement of the material within a sunk or recessed portion, all of which present well defined lines 30 and hence form a firm guide for the workman. This permits such work to be attended to by ordinary workmen where a painted sign would require a skilled sign painter or letterer.

35 While I have so far described the sign as being composed of a bright metal plate and dark body filler material, I may reverse the characteristics of the materials and use a plate of dark material and a body filler 40 material of a light material.

When it is desirable to have black letters formed by the plate I may use the construction shown in Fig. 6, wherein 7 is a plate formed of the material such as to be unaffected by atmospheric conditions and dark 45 in color, such for example, as a very pure and hence non-oxidizable iron. Therein the letters are formed by offsetting them outwardly from the original plane of the 50 metal, one such offset portion being indicated by 8. In this instance I build upon and surround the letters with a body filler material 9, likewise of such character as to be unaffected by atmospheric conditions and 55 having a white or bright color. One such suitable material is ground or pulverized aluminum secured together by a suitable binder such that it can be applied in plastic form to the plate and thereafter sufficiently 60 set or harden to adhere firmly to the plate. In this manner a sign having dark letters within a surrounding or bright mat is secured.

Another method of securing white or 65 bright letters upon a black or dark back-

ground is illustrated in Fig. 7, wherein the plate 10, which is composed for example of treated or coated iron or some other dark material that is practically unaffected by atmospheric conditions, is provided with depressed letters, one of which is indicated at 70 11, thus forming a recess in the plate corresponding in form to the form of the letter or figure. In the recess thus formed I place the body filler material 12, which is of a 75 white or bright color and of such character as to be unaffected by atmospheric conditions, for example, ground or flake aluminum, secured into an adhering mass by a suitable binder. In this manner a sign is 80 secured in which the plate forms the black or dark mat and in which the bright letters are formed by the filler material.

While I have illustrated signs in which the letters are formed, in one instance of white 85 bright material and in the other instance of black or dark material, I prefer the bright letters with surrounding mat or background of black, for the reason that a smaller bright letter upon a black background has the appearance of a letter of much larger size, due to the phenomenon of irradiation, and for this reason can be read at a greater distance and also in less light.

It thus becomes apparent that my inventive idea may be embodied in a variety of forms, but that in all thereof will be found the characteristic of two contrasting color materials which are preferably of such character as to be substantially unaffected by atmospheric conditions, of sunlight, gases, water, etc., I shall hereinafter refer to them as "atmospherically permanent" materials, and to that character of material in virtue of which it may be struck by a missile without fracturing or chipping as an "infrangible material."

Since this disclosure will readily suggest to others skilled in the art to which this 100 pertains, various modified forms of signs and modifications of the method of producing same, I do not wish to be limited to the specific materials herein described, nor to the form of the sign herein shown, nor to the precise method of producing same, except only as may be necessary by limitations in the hereunto appended claims.

The word "plastic," as used in the claims, is to be construed broadly and includes plastic compositions as well as "plastics" strictly 110 defined.

I claim:

1. A sign embodying therein two atmospherically permanent color contrasting materials, one thereof being a bright metal 125 plate having characters therein offset from the plane of the body of the plate and the other a bituminous body filler material carried by the plate, of a thickness extending a considerable distance up the sides of the 130

- characters, and co-acting with the offset characters thereof in forming a contrast between the characters and surrounding portion.
- 5 2. A sign embodying therein two atmospherically permanent color contrasting materials, one thereof being an aluminum plate having integrally upwardly formed bright metal characters therein and the other 10 a bituminous body filler material surrounding the characters and forming a mat or background therefor and of a thickness extending a considerable distance up the sides of the characters.
- 15 3. A sign embodying therein two atmospherically permanent color-contrasting materials, one thereof being a plate in which

characters are provided in a plane offset from the plane of the body of the plate and the other a body plastic filler material carried by the plate, of a thickness sufficient to extend from the base of the characters at least a considerable distance up the sides thereof, and co-acting with the character portions in forming a contrast between the 20 25 characters and surrounding portion.

In testimony whereof, I have hereunto set my hand, this 27th day of February, 1919, in the presence of two subscribing witnesses.

HERMAN P. ANDRESEN.
